UNITED STATES PATENT OFFICE.

VIRGILIO COLZI AND FELICE BARDELLI, OF TURIN, ITALY.

TELEMETER.

1,080,421.

Specification of Letters Patent.

Patented Dec. 2, 1913.

Application filed March 3, 1910. Serial No. 547,137.

To all whom it may concern:

Be it known that we, VIRGILIO COLZI and FELICE BARDELLI, both subjects of the King of Italy, residing at 18 Via Roma, Turin, Italy, have invented certain new and useful Improvements in Telemeters; and we do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 The present invention relates to telemeters having a fixed base and instantly giving the distance of a distant object sighted, by a single observation, and has for its object improved modifications of the telemeter described in our Patent No. 1,058,556, dated April 8, 1913.

20 The main features of the present improvement relate to the telescopic system, the measuring device, the rectifying device, and 25 the means for supporting or suspending the instrument, as will hereinafter be more fully described and particularly pointed out in the claims.

In the accompanying drawings, showing 30 by way of example, one form of our improved telemeter, and in which like parts are similarly designated—Figure 1 shows the field of the eye piece or ocular of the telemeter. Fig. 2 is a perspective view of 35 the central system of erecting prisms and the associated prisms of the rectifying system. Figs. 3 and 3^a are diagrams showing the action of a rotating prism on a luminous ray. Figs. 4 and 5 show prisms forming the optical part of a measuring device having, respectively, two and three prisms and made and operating in accordance with the present invention. Fig. 6 is a diagrammatical 40 elevation of the telescopic and rectifying systems. Fig. 7 is a horizontal longitudinal section through the telemeter on line 7—7 of Fig. 12. Fig. 8 is an elevation of one of the prisms of the objectives. Figs. 9 and 10 show the field of the eye piece of the rectifying system in two positions. Fig. 11 shows the telemeter in rear elevation with its supporting tube in vertical longitudinal section. Fig. 12 is a front elevation. Fig. 13 is a section on line 13—13 of Fig. 55 11. Fig. 14 is a cross-section showing the

relative position of the oculars and the separating prism.

It has been found in practice that the upper and lower portions of the image, 1 and 2, Fig. 1, are simultaneously visible in a diminished or paler condition, as indicated at 3 and 4, notwithstanding the use of the thin opaque plate or sector 5 in the horizontal plane of the division between the upper and lower halves of the images at the eye piece. 60 Such phantom image, or double representation, is confusing to unskilled observers, and it is desirable that the two portions 1 and 2 only of the image be visible in the eye piece. It also causes the images at ordinary distances to be less distinct. We have overcome this objection and annoyance to unskilled observers by cutting the prism 6 of the erecting system, Fig. 2, in the plane of reflection 7 of the opaque 65 sector 5, i. e., in a plane parallel to the emergent face of the prism, and cementing the parts together again. The plane 7 constitutes therefore a sort of prolongation of the sector 5 in the direction of 70 its reflection and prevents the oblique luminous rays from near the junction of the two prisms, 8, 9, from passing beyond this plane. The images 1 and 2, Fig. 1, are rendered clear, and those less sharp, or phantom, images, 3 and 4, are avoided.

75 The measuring device, which is the most important part of the present invention, consists in its essential form of two prisms whose refracting edges are adjacent and 80 parallel, so that when in closed position they act substantially as a single glass having parallel or nearly parallel faces. In the present invention these two prisms are mounted to rotate in a plane perpendicular 85 to their parallel refracting edges and thereby open with respect to one another angularly or like a fan. This measuring device is founded on the following principle: A luminous ray R, Fig. 3, passing through the prism P is deviated or refracted to R', being bent toward the base of the prism. When the prism P is moved to the right or left of a plane perpendicular to its base and through its refracting edge, in this instance 90 the vertical plane, the ray R becomes refracted to a greater extent, that is, through a wider angle. In the position of the prism p, the ray R is deviated to r, and in the position p₁ to r₁. The deviation of the ray R in 95 100 105 110 115 120

creases not only with the increase in the angle of rotation of the prism P , but to a greater extent, so that equal successive angles of rotation of the prism produce increasing deviation, each greater than the preceding one. It is upon this fact and action that our novel measuring device is based. One prism alone, however, is not sufficient to constitute a proper measuring device, not only by reason of coloring the images, (chromatic aberrations) but chiefly on account of the deformation of the images, the deformation being so great as to destroy their details. This deformation may be prevented by assembling two identical prisms and causing them to rotate to equal extents in opposite directions, thereby compensating the deformation, and to this end the measuring device will assume the form shown in Fig. 4. It is still necessary, or desirable, to obviate the coloring of the images, due to dispersion. This may be done in two ways, either by using two achromatic prisms, or by inserting a third stationary prism which is termed the neutralizer between two prisms P . This third, stationary prism may have an angle twice that of the movable prisms, or may be of flint or crown glass. Such an arrangement is shown in Fig. 5 which is the preferred form, and the system of three prisms will be equal to a glass having parallel faces, when the laterally movable prisms are in their initial or closed position.

The construction may be made general by adopting two movable prisms having different angles, in which case the stationary neutralizing prism must have an angle equal to the sum of the angles of the two movable prisms.

If the three prisms are all of the same kind of glass, dispersion will be produced when the two movable prisms have reached their useful maximum movement or rotation, which may be 40° or thereabout, for each prism. In this case it will be necessary either to make all the prisms achromatic, or make the neutralizer of flint or crown glass with an angle capable of correcting, slightly in excess, the dispersing power of the two movable prisms when in their initial or closed position, and not quite capable of fully correcting the defect when the two movable prisms have been moved to their maximum extent.

It will be understood that in order to always obtain perfect images the movable prisms should rotate by slightly different amounts, and this difference must be determined by experiment for each instrument. This difference in the angle or speed of rotation of one of the movable prisms with respect to the other, will be, of course, less when the two prisms have a different angle of refraction, as in the general case above

referred to, and it will be an inverse function of said difference between the angles of refraction. It will also be necessary to determine it by experiment for each difference of angular amplitude and in each instrument. In this measuring device the luminous ray is deviated by a slight movement of the movable prisms, and as already remarked, is deviated by an amount constantly increasing with each unit increase of opening of the prisms or rotation from their initial position. In known measuring devices the luminous ray, under the same conditions, has always an equal deviation. Consequently in this device in order to obtain a uniform rate of deviation of the ray for equal angular movements of the prisms, it will be necessary to effect a rapid movement of rotation of the prisms at the beginning of their movement from their initial positions, and a slower one toward the end of their movement. In other words, the speed of rotation varies inversely as the angle between the two prisms, while in known devices the angle of rotation of the two prisms must be constant, or nearly so.

The closed measuring device is mounted for viewing objects at the greatest distance and its rotation is the greater the nearer the object observed, the maximum distance of the object corresponding to a minimum rotation of the prisms, and the minimum distance to the maximum rotation. It is also known that the displacement of the image of the object observed greatly increases as the object is approached. From this fact combined with the manner of operating the measuring device above described it results that:—*a.* In known measuring devices the movement of the prisms and consequently the displacement of the scales fixed thereto, is relatively small for a distant object approaching, for instance from 6,000 to 5,000 meters and considerably greater for an object moving by the same amount but closer, for instance approaching from 3,000 to 2,000 meters. *b.* In the measuring device made in accordance with our present invention, the rotation of the prisms and consequently the displacement of the measuring scales is somewhat increased for distant objects and considerably reduced for closer ones. Therefore the scales in the known measuring devices must be graduated with lines drawn very close to one another for distant objects, and with lines wider apart the nearer the object. In the present measuring device the scales are graduated uniformly or practically so, owing to the compensation for the displacement of the image and for the rotation of the prisms, which rotation must decrease as the object is approached. Moreover, as the decrease in the spaces between the lines of the scales for close objects in the known forms is much greater than the in-

crease in the spaces between the lines of the scale in the present invention, the net result in the present invention is that the scales will be considerably shorter and more accurate. These scales are engraved on adjacent concentric circular sectors.

The detailed mechanical construction of the present measuring device and the mounting therefor are not described herein, as they 10 may be of any type, and any manufacturer of optical instruments may easily make them, this being no part of the present invention.

In the present telemeter we have omitted 15 the deviating prism 38 of our prior mentioned application, and use only the glass 39 with parallel faces for the purpose of facilitating the observing of an object of small height or a point. In Figs. 6 and 7 this 20 glass 39 is shown placed in the path of the rays of light coming from the objective 21 and rotated by means of a horizontal shaft or pin 40 having a head 41. This glass when positioned perpendicular to the optical axis 25 X—X of the objectives 20 and 21 acts simply as a glass, *i. e.*, without refraction, while if placed at an angle to said axis it acts as a prism, so that it is possible to view conveniently an object of small height, or even 30 a point.

The rectifying device.—This device, Figs. 6 and 7, comprises two prisms, 10 and 11, two identical lenticular elements or lenses 12, 13, and two crossed prisms, 14, 15, Figs. 35 2, 6 and 7, inserted between the prisms 8 and 9, that is, their hypotenuses or reflecting faces are parallel with and adjacent the hypotenuses of the prisms 9 and 8, respectively.

40 The upper and lower halves of the incident faces of the objective prisms 16 and 17 may be silvered, as in our prior application, but in lieu of the silvering we prefer to cement on each of said prisms a glass 45 mirror, shown at 18 and 19, with the reflecting surface of the mirror slightly oblique to the incident face and converging the reflected rays toward the optical axis X—X.

The prisms 10 and 11 are mounted so that 50 one of their sides is perpendicular to the optical axis X—X, and the other is parallel thereto, so that their hypotenuses which are the reflecting faces of these prisms, direct the rays of light, as 22, and 23, coming 55 through openings 29 and 30 in the telemeter case, Figs. 7 and 12, and through the faces of the prisms parallel with the axis X—X, in a direction parallel to the optical axis X—X, then through their coöperating 60 prisms 14 and 15 respectively. These prisms 10 and 11 are thinner than the prisms 14, 15, and are arranged opposite the upper and lower halves respectively of said prisms 14 and 15, Fig. 6.

65 On the emergent faces of prisms 10 and

11, namely those faces opposite the lenses 20 and 21 are engraved the scales, the scale on one of which, for example, is divided into tenths of a millimeter, while the scale on the other is divided so as to constitute a 70 nonius or vernier for the first one. Owing to this arrangement the two scales may be seen in the field of the eye piece 24, as shown in Fig. 9.

The operation of this device is as follows: 75 Assuming that the two prisms 16 and 17 have been adjusted so as to cause the two parts of the image of an object located at a great distance, *ad infinitum*, to coincide in the ocular field 25 of the telemeter when 80 the prisms P, P, of the measuring device are also in their position corresponding to the distance of said object; the field of the eye piece is then observed and the respective positions of the two scales or scale and vernier 85 noted. In Fig. 9, which is assumed to represent this field of the eye piece after said adjustment, the reading gives, for example, 90 6.3. It is evident that as long as the positions of the two scales in the field of the eye piece 24 have not changed, the exact desired positions of the prisms 16 and 17 have not altered. It will then be necessary immediately before determining a distance with the instrument, to be sure that the relative positions of the two scales in the field of the eye 95 piece 24 have not altered. If, on the contrary, it is found that the reading has altered, owing to any deformation of the instrument, by reason of temperature changes 100 or otherwise, and the reading should be, for example that shown in Fig. 10, namely 7.1, the reading is at once rectified by the aid of the glass 26 having parallel plane faces, which is then rotated by means of the head 105 27 on rod 27^a forming a vertical axis on which the glass is rotated, Figs. 7 and 11. As long as this glass 26 remains perpendicular to the path of the rays coming through the objective 21 it will not produce any deviation, but when it is inclined thereto said rays will be deviated, after passing through the glass, parallel to their original direction. Therefore, by suitably positioning the glass 110 26 it is possible to deviate said rays so as to produce on the focal plane of the objective 24 the image of the scale on prism 11 correctly with respect to the image of its companion scale and bring the two to initial 115 position, Fig. 9.

The two eye pieces 24 and 25, Figs. 7 and 11, are mounted on the same rotating washer or support 28, so that either one or the other may be used for the purpose of telemetric observation as well as for reading the scales 120 of the rectifying device.

The above described rectifying device may serve to check the reading of the distance on the scales of the measuring device.

Assuming that the instrument has been 125

adjusted, then, after the displacement of the prisms of the measuring device, in order to cause the two parts of the image of the viewed object to coincide or register in the field of the eye piece of the telemeter, the field of the eye piece of the rectifying device is observed, and it will be found that the lower scale has been displaced due to the rotation of the prisms of the measuring device. The displacement of this scale read by means of the upper scale or vernier, the position of which has not changed, is in direct proportion to the displacement of the prisms of the measuring device, and consequently to the distance of the viewed object; the extent of this displacement checks the reading effected by the measuring device.

The prisms 10 and 11 are illuminated through the slots 29 and 30 provided in the casing 31 of the telemeter, Figs. 7 and 12. These openings may be circular, as shown in dotted lines in Fig. 12, and may be provided with lenses in order to concentrate a greater quantity of light on the prisms 10 and 11.

The mounting of the instrument inside a protecting tube 31 is such as to render the instrument insensible to or unaffected by either the elastic or the permanent deformations of the tube, and especially those changes due to temperature variations. This is attained by causing the whole telemeter to rest on four points, placed in pairs, and the points of a pair diametrically opposite and located on two vertical diameters so distanced from the center of the telemeter that its weight is equally distributed on both sides of these supports.

The points of support are on four steel balls 32 located in steel seats 33 mounted in or connected to the intermediate rings 34 of the telemeter body. These balls also seat in plates 35 secured by screws 36, Fig. 13, to the outside of the tube 31, Figs. 11, 12 and 13. The radii of curvature of the seats 33 is slightly greater than the radius of the balls 32, so that the latter contact with the seats at one point only. Therefore, whatever the dilation of the tube 31 it will not produce any deformation of the telemeter body. Even torsion or flexure (especially the bending in a horizontal plane so harmful to optical mechanism) of the tube 31 is not transmitted to the telemeter body, owing to said suspension at the four points with the play between the balls and their seats.

We claim:—

1. In a telemeter, the combination with an opaque sector, of a totally reflecting prism composed of two portions cemented together, the plane of cementation lying in the plane of reflection of said sector in said prism.

2. In a telemeter, the combination with an opaque sector of a totally reflecting prism composed of two portions cemented to-

gether, said sector positioned proximate the upper half of the emergent face of the prism, and the plane of cementation lying in the plane of reflection of said sector in said prism.

3. In a telemeter, the combination with an opaque sector, of a totally reflecting right-angular prism composed of two portions cemented together in a plane parallel to its hypotenuse and the sector positioned opposite the end of said plane perpendicular to the hypotenuse.

4. In a telemeter, the combination with a thin opaque sector, of a totally reflecting right-angular prism composed of two portions cemented together in a plane parallel to its hypotenuse, said sector positioned perpendicular to and substantially bisecting one half of the hypotenuse or emergent face of the prism and opposite one end of the plane of cementation.

5. In a telemeter, the combination with a two part cemented totally reflecting prism, of an opaque sector coöperating in conjunction with the plane of cementation of said prism to separate the images distinctly into two portions and avoid the formation of phantom images.

6. In a telemeter, a measuring device comprising a pair of prisms perpendicular to the optical axis of the telemeter and oppositely rotatable in a plane perpendicular to their refracting edges.

7. In a telemeter, a measuring device comprising a pair of prisms in and perpendicular to the optical axis of the telemeter and oppositely rotatable in planes perpendicular to their refracting edges at different angular speeds.

8. In a telemeter, a measuring instrument comprising a pair of prisms in and perpendicular to the optical axis of the telemeter and oppositely rotatable in planes perpendicular to their refracting edges, and means to chromatically correct said prisms.

9. In a telemeter, a measuring instrument comprising a pair of prisms in and perpendicular to the optical axis of the telemeter and oppositely rotatable in planes perpendicular to their refracting edges, said prisms being movable at different angular speeds and means to chromatically correct said prisms.

10. In a telemeter, a measuring instrument comprising two prisms in and perpendicular to the optical axis of the telemeter and a third prism located between them whose refracting angle is substantially equal to the sum of the refracting angles of the other two prisms.

11. In a telemeter, a measuring instrument comprising two equal parallel prisms in and perpendicular to the optical axis of the telemeter and rotatable in planes perpendicular to their refracting edges, and a third

inverted prism located between them whose refracting angle is equal to the sum of the refracting angles of the parallel prisms.

12. In a telemeter, a measuring device comprising two equal right triangle prisms in and perpendicular to an optical axis of the telemeter, and a third inverted prism located between them whose refracting angle is double the refracting angle of one of the parallel prisms said parallel prisms being oppositely rotatable in planes perpendicular to their refracting edges.

13. In a telemeter, a measuring device comprising two equal right triangle prisms in and perpendicular to the optical axis of the telemeter, and a third inverted prism located between them whose refracting angle is double the refracting angle of one of the parallel prisms said parallel prisms being oppositely rotatable in planes perpendicular to their refracting edges at different angular speeds.

14. In a telemeter, a measuring device comprising two equal right triangle prisms in and perpendicular to an optical axis of the telemeter, and a third inverted prism located between them whose refracting angle is double the refracting angle of one of the parallel prisms said parallel prisms being oppositely rotatable in planes perpendicular to their refracting edges and whose outer faces are parallel to one another when in zero position.

15. In a telemeter, a measuring device comprising a pair of prisms in and perpendicular to the optical axis of the telemeter oppositely rotatable in planes perpendicular to their refracting edges at different angular speeds, and a glass having plane parallel faces in and perpendicular to the optical axis pivoted to swing at an angle to said axis to correct for errors arising in deformation of the instrument.

16. In a telemeter, a measuring instrument comprising a pair of prisms in and perpendicular to the optical axis of the telemeter and oppositely rotatable in planes perpendicular to their refracting edges, said prisms movable at different angular speeds and means to chromatically correct said prisms and a glass having plane parallel faces in and perpendicular to the optical axis pivoted to swing at an angle to said axis to correct for errors arising in deformation of the instrument.

17. In a telemeter, the combination with the erecting prisms thereof; of a measuring device to one side of said prisms, comprising parallel equal, right angle prisms in and perpendicular to the optical axis of the telemeter oppositely movable at different angular speeds in planes perpendicular to their refracting edges and a stationary inverted prism whose refracting angle is equal to the sum of the refracting angles of the movable

prisms, the outer faces of which said movable prisms are parallel when in zero position and a glass having plane parallel faces to the other side of said erecting prisms in and perpendicular to the optical axis of the telemeter and mounted to move at angles to said axis.

18. The combination with a telemeter having objective prisms, each having a reflector on a portion of its face, of an eye piece, a pair of crossed reflecting prisms reflecting into the same, a prism on each side of said crossed prisms, having an index on one of its faces, means to illumine the latter prisms to direct the light to the said reflectors which in turn reflect the light to the crossed prisms.

19. The combination with a telemeter having two objective prisms, one having a reflector on the upper half of its forward face and the other on the lower half of its forward face; of an eye piece, a pair of crossed juxtaposed prisms reflecting directly into the same, a prism on each side of said crossed prisms, less in height than one of them, an index on the emergent face of each of said latter prisms directed toward said reflectors and means to separately illumine the latter prisms.

20. The combination with a telemeter having two oppositely situated objective prisms, of a reflector on the upper half of the incident face of one and the lower half of the incident face of the other slightly inclined to said face, an eye piece, a pair of superposed juxtaposed crossed prisms reflecting directly into said eye piece, a prism opposite each of the crossed prisms of less height than said crossed prisms and located respectively above and below the optical axis of the telemeter, one of said prisms having engraved on its emergent face a scale and on the emergent face of the other, a vernier, means to separately illumine the latter prisms whereby they will direct light to the reflectors which in turn will reflect to the crossed prisms that again reflect to the eye piece where the scale and vernier are viewed in proper relation to one another.

21. The combination with a telemeter having light receiving prisms, each having a reflector on a portion of its face, of an eye piece, a pair of crossed reflecting prisms reflecting into the same, a side prism on each side of said crossed prisms, having an index on one of its faces, means to illumine the latter prisms and direct the light reflected from said side prisms to the said reflectors which in turn reflect the light to the crossed prisms, and means to deflect the rays from one of the reflectors into a parallel path before reaching the crossed prisms.

22. The combination with a telemeter having light receiving prisms, each having a reflector on a portion of its face, of an eye piece, a pair of crossed reflecting prisms re-

6
flecting into the same, a prism on each side of said crossed prisms, having an index on one of its faces, means to illumine the latter prisms to direct the light to the said reflectors which in turn reflect the light to the crossed prisms, and optical means to compensate for deformations of the telemeter.

23. The combination with a telemeter having two oppositely situated objective prisms, 10 of a reflector on the upper half of the incident face of one and the lower half of the incident face of the other slightly inclined to said face, an eye piece, a pair of superposed juxtaposed crossed prisms reflecting 15 directly into said eye piece, a prism opposite each of the crossed prisms of less height than said crossed prisms and located respectively above and below the optical axis of the telemeter, one of said prisms having engraved

20 on its emergent face a scale and on the emergent face of the other, a vernier, means to separately illumine the latter prisms whereby they will direct light to the reflectors which in turn will reflect to the crossed prisms that again reflect to the eye piece 25 where the scale and vernier are viewed in proper relation to one another, and a rotatable glass having plane parallel faces in the path of the rays reflected by one of the reflectors.

30 In testimony that we claim the foregoing as our invention, we have signed our names in presence of two subscribing witnesses.
